UNITED STATES PATENT OFFICE.

THOMAS TERRENCE ROGAN AND EDWARD B. WRIGHT, OF FITCHBURG, MASSACHUSETTS.

PAPER-MAKING MACHINE.

Application filed November 16, 1922. Serial No. 601,398.

Our invention relates to paper making machines, and particularly to Fourdrinier machines.

One of the objects of the invention is to provide a simple, practical and advantageous form of Fourdrinier machine.

Another object of the invention is generally to improve the formation of the paper.

Other objects of the invention are to increase the strength of the paper and make it uniform, to require less sulphite and thereby require less beating and less power, to permit operation of the machine with less skilled help, to avoid interference with the changing of the deckels for different widths of sheet, and to secure automatic action controlling the formation in accordance with the speed of the machine.

In the accompanying drawings Fig. 1 is a side elevation of a paper making machine embodying our present invention;

Fig. 2 is a cross section taken on line 2—2 in Fig. 1;

Figs. 3 and 4 are views of details of construction.

Referring to the drawings, we show an end portion of a paper making machine wherein in the pond or feed box is indicated as 1, deckel wheels as 2—2, deckel straps as 3—3, table as 4, and table rolls as 5—5. The wire traveling over the table rolls 5 is shown at 6, the breast roll as 7, and a rotary shaft therefor as 8. Two gates or slices 9—9 are shown in the pond or feed box 1, although only one could be used.

In accordance with our invention we show an agitating device for agitating and mixing the stock and water, and this is preferably located in the pond or feed box 1. The form of agitating device shown preferably comprises a rotary shaft 10 arranged in the feed box 1, preferably between the two slices 9—9, when two are used, or just inside the opening when one is used, and provided with a series of agitating parallel blades 11—11 located at intervals along said shaft 10. The rotary shaft 10 may be mounted in bearings 12—12 on stands or pedestals 13—13 resting on the bed plate of the machine.

As a preferred arrangement the agitator is driven by some operating part of the machine, as for example, by driving it from the rotary breast roll shaft 8 by means of a belt 14, whereby the action of the agitator 55 will vary in accordance with the speed of the breast roll.

Thus it will be seen that the agitating device comprising the rotary shaft 10 with screw blades or members 11 thereon will 60 agitate the pulp as it is about to pass out of the pond or feed box 1 on to the wire 6, and will thereby thoroughly mix the stock and water so that when the stock passes under the slice to the wire, the formation in 65 the resulting paper sheet will be greatly improved. It will be made stronger and more uniform, the increased strength being sufficient to show very clearly on a strength tester. Furthermore, it will require less 70 sulphite and will accordingly necessitate less beating and therefore less power will be required in running the machine and an economy of power will result. Furthermore, less skilled labor will be required from machine 75 tenders, and a saving will be effected there. Furthermore, the deckels can be changed to make any width of sheet without interfering with the agitating device. The latter can obviously be used with one or more 80 slices in the pond or feed box. Furthermore, the speed of the agitator and consequently its action will vary according as the speed of the machine varies and consequently a greater or less agitation will take place according as the machine runs faster or slower.

It will be understood that changes and modifications may be made without departing from the spirit of the invention.

What we claim is:

1. In a Fourdrinier machine, a pulp agitating device arranged within the feed box near the wiring opening thereof, said agitating device comprising a rotary member provided with devices for shifting the pulp laterally of the direction of movement of the wire.

2. A Fourdrinier machine having an agitating device arranged within the feed box near the wire opening thereof, said agitat-

2
ing device comprising a rotary shaft carrying a series of radially arranged screw or spiral agitating blades.

3. A Fourdrinier machine having pulp agitating mechanism comprising a rotary member provided with a plurality of radially arranged blades mounted on said member at intervals and provided with inclined

surfaces adapted to throw the pulp sidewise as well as longitudinally of the machine. 10

In witness whereof, we hereunto subscribe our names this 13th day of November A. D., 1922.

THOMAS TERRENCE ROGAN.
EDWARD B. WRIGHT.
